COMBINATION LIGHTER AND FLASHLIGHT

Edmund Szamborski, Woodside, N. Y.

Application February 27, 1956, Serial No. 40,372

Term of patent 3½ years

(Cl. D48—27)

FIG 1

FIG 4

Fig. 1 is a top plan view of a combination lighter and flashlight showing my new and ornamental design.

Fig. 2 is a side elevational view.

Fig. 3 is an end elevational view.

Fig. 4 is a bottom plan view.

I claim:

The ornamental design for a combination lighter and flashlight, substantially as shown.
